(74) Attorney, Agent, or Firm — Loza & Loza, LLP;
Heidi Eisenhut(57) **CLAIM**

I claim the ornamental design for a guide for cables, as shown and described.

DESCRIPTION

FIG. 1 is a top right perspective view of a guide for cables of my invention;

FIG. 2 is a front view thereof;

FIG. 3 is a rear view thereof;

FIG. 4 is a right side thereof;

FIG. 5 is a left side view thereof;

FIG. 6 is a bottom view thereof;

FIG. 7 is a bottom perspective view thereof;

FIG. 8 is a top view thereof; and,

FIG. 9 is a top left perspective view thereof.

The broken lines showing of the cables in FIG. 8 illustrates the environment of the claimed design and forms no part thereof.

1 Claim, 9 Drawing Sheets(56)
